(57) **CLAIM**

The ornamental design for an infant safety car seat with wheels as shown and described.

DESCRIPTION

2. Infant safety car seat with wheels

2.1: Perspective view in a first state

2.2: Left side view in a first state

2.3: Perspective view in a second state

2.4: Left side view in a second state

2.5: Perspective view in a third state

2.6: Left side view in a third state

2.7: Left side view in a fourth state

2.8: Perspective view in a fourth state

2.9: Top view in a first state

2.10: Top view in a second state

2.11: Top view in a third state

2.12: Top view in a fourth state

2.13: Front view in a first state

2.14: Right side view in a first state

2.15: Rear view in a first state

2.16: Bottom view in a first state

2.17: Front view in a second state

2.18: Right side view in a second state

2.19: Rear view in a second state

2.20: Bottom view in a second state

(Continued)

- 2.21:** Front view in a third state
2.22: Right side view in a third state
2.23: Rear view in a third state
2.24: Bottom view in a third state
2.25: Front view in a fourth state
2.26: Right side view in a fourth state
2.27: Rear view in a fourth state
2.28: Bottom view in a fourth state

In the reproductions, the broken lines show portions of the product that form no part of the claimed design.
